UNITED STATES PATENT OFFICE.

CHARLES L. DAVIS, OF MERIDEN, CONNECTICUT, ASSIGNOR TO WILCOX & WHITE COMPANY, OF MERIDEN, CONNECTICUT, A CORPORATION OF CONNECTICUT.

MUSIC-SHEET FOR MECHANICAL MUSICAL INSTRUMENTS.

SPECIFICATION forming part of Letters Patent No. 736,228, dated August 11, 1903.

Original application filed November 12, 1902, Serial No. 130,960. Divided and this application filed March 17, 1903. Serial No. 148,177. (No model.)

To all whom it may concern:

Be it known that I, CHARLES L. DAVIS, a citizen of the United States, residing at Meriden, in the county of New Haven and State of Connecticut, have invented a new and useful Improved Music-Sheet for Mechanical Musical Instruments, of which the following, together with the accompanying drawings, is a specification sufficiently full, clear, and exact

- 5 to enable persons skilled in the art to which this invention appertains to make and use the same.
- My present invention relates to the construction of perforated music sheets, rolls, or 5 strips for pneumatically-controlled music-playing instruments, the objects being to provide a music-sheet adapted for use in connection with a pneumatic instrument having a tracker wherein a portion or portions of the 20 orifices are formed on a more contracted spacing than its normal scale.

Another object is to provide in the music-sheets for pneumatic piano-playing instruments a combined scale or note space system 25 that will give a large number of notes on a comparatively narrow strip or music-sheet to increase the number of notes represented without increasing the width of the music-sheet to an excessive extent.

- 30 Another object is to provide a music sheet or strip having a range of music-note perforations formed on a determined uniformly-spaced scale and supplemented at either or both sides thereof with a marginal series of 35 music-note perforations formed on a more contracted scale, as hereinafter explained.

My invention consists in providing a music sheet or strip in the main body or principal part of which the perforations are formed on 40 a regular uniformly-spaced scale and of normal width of slot or circular-hole perforations and comprising a marginal or side portion having the perforations therein formed on a narrower or more condensed scale with 45 slots or holes uniformly spaced, but of smaller lateral dimension than those in the main body of the sheet, as more fully hereinafter described, and illustrated in the accompanying drawings, in which—

Figure 1 represents a portion of a music-sheet embodying my invention. The lines thereon indicate the scales or rows of note-openings. Fig. 2 represents the face of a tracker upon which my music-sheet is adapted to be employed. 50

In the illustrations the delineation is shortened to bring the figures within the limits of the drawing-sheet by omitting twenty-four notes at the central portion of each figure; but it will be understood that such omitted 60 portion is in regular uniform continuation of the normal scale shown adjacent to the break and may account for a width of note perforations. 55

My improved music-sheet, as illustrated in Fig. 1, is constructed of a paper sheet or strip M of any required length. The central main portion R² has the perforations 13 therein formed and arranged on a normal uniformly-spaced scale of, say, six to the inch 65 or other suitable determined number and comprising, say, sixty-five notes, corresponding with the scale of the main series R of the tracker-ducts 3, and said music-sheet is provided with a supplementary or marginal portion S² at either or both edges, in which the perforations 15 for a series of, say, ten notes, more or less, are formed on a narrower or more contracted scale or a scale of, say, ten notes to the inch or other suitable determined number and with openings that are 70 smaller laterally than the perforations 13 of the main series, thus making the full scale 75 range eighty-five notes. The lines of smaller perforations are on a scale to correspond with that of the supplementary series S of openings 5 in the tracker-face A. By this construction I produce a music-sheet comprising a larger number of notes without requiring a sheet or strip of excessive width and without 80 reducing the scale of the music-note perforations or ducts in that part of the range within which the greater portions of most music is written. In some instances the perforations for single short notes of the supplementary series or narrow scale portions S² may be formed as oblong holes, as at 31, having a length 85 equal to the diameter of the single short-note 90 95

hole 13^a of the larger scale, but with a lateral width of opening less than the diameter of the larger scale-holes. The openings for long notes may be formed as slots, as at 20, or a 5 series of successive adjacent holes similar to the short-note holes, as at 25. The cross-bridges, being of less dimension than the tracker-orifices, will not cut off the air while passing such orifices. Consequently the primary pneumatic remains flushed until such 10 long-note perforations have wholly passed the orifice.

A tracker of the class upon which my improved sheet-music is designed to be used 5 has its face A provided with orifices 3 and 5, arranged as shown in Fig. 2, the portion R corresponding to the main series of sixty-five note-perforations and the portions S corresponding to the marginal series of ten note- 10 perforations. Such tracker forms the subject-matter of a separate application for Letters Patent.

In this specification, for convenience of description, I have considered as the range of 25 the music-sheet the perforations for sixty-five notes and eighty-five notes; but I do not confine my invention to these exact numbers of notes, since the number of notes in either the main or the marginal series can be more 30 or less without change in the nature of the invention.

I am aware that music-sheets have been heretofore made with perforations of different widths arranged in gradually decreasing 35 or increasing scale to compensate for the shrinking or expansion of the paper due to climatic influence or changes of humidity, also that sheets have been provided with openings of different character from the note- 40 perforations for the engagement of feed-cogs or devices for advancing the sheet.

What I claim, and desire to secure by Letters Patent, is—

1. A perforated music sheet, strip or band for mechanical music-playing instruments, 45 having a main series of perforations formed on a uniformly-spaced scale of a determined number to the inch, across the central portion of the sheet, and having at the side a supplementary series of perforations formed on a laterally-condensed scale or with greater 50 number to the inch than those in the main series, the perforations of the main series, and of the supplemental series, being of different lengths for the purpose set forth. 55

2. A perforated music sheet, strip, or band for mechanical music-playing instruments, having the main series of note-perforations across its central portion formed on a uniformly-spaced scale with holes of a determined size, and provided at the sides or marginal portions thereof with supplementary series of music-playing perforations that are formed on a uniformly-spaced scale, of less-width spacings and with holes of less lateral 65 dimension than the main series, the perforations being of different lengths, substantially as described. 60

3. A perforated music sheet or roll for the purpose specified, its perforations comprising 70 a plurality of different scales, each uniformly spaced within its limit, the single short-note perforations for the wider-scaled portion being formed as circular holes of determined size, and the single short-note perforations on 75 the narrower-scaled portions being formed as longitudinally oblong holes, of a length which corresponds to the diameter of said circular holes, and of a width less than the diameter of such circular holes. 80

Witness my hand this 11th day of March, 1903.

CHARLES L. DAVIS.
